UNITED STATES PATENT OFFICE.

HERMAN C. WALDMAN, OF ST. LOUIS, MISSOURI.

FIRE STOP FOR ELEVATOR DOORS.

Application filed July 28, 1922. Serial No. 578,264.

To all whom it may concern:

Be it known that I, HERMAN C. WALDMAN, a citizen of the United States, residing at St. Louis, Missouri, have invented a certain new and useful Improvement in Fire Stops for Elevator Doors, of which the following is a full, clear, and exact description, such as will enable others skilled in the art to which it appertains to make and use the

This invention relates to counterbalanced fire doors for elevator shafts, and particularly horizontally-divided fire doors of the type in which the top and bottom sections of the door are arranged in parallel relation to each other, but in different vertical planes, so as to provide a space between the top section of the door and the lintel of the door opening that will receive the bottom section of a vertically-aligned door of the same type located on the floor above, when said upper door is moved into its open position, such doors being used principally in buildings in which the distance between the lintel of a door opening and the floor above is not deep enough to receive two door sections that lie in the same vertical plane, one above the other.

Owing to the fact that the top section of such a door is spaced away from the lintel of the door opening when the door is in its closed position, there is danger of fire escaping from the elevator shaft into the room or from the room into the elevator shaft through the space between said lintel and top door section.

The main object of my present invention is to provide an efficient means of novel construction for closing the space between the lintel of the door opening and the top section of the door that will not interfere with the downward movement of the bottom section of the vertically-aligned door located at the floor above.

Figure 1 is a vertical sectional view, illustrating a fire door structure embodying my invention, in which the means for closing the space between the top section of the door and the lintel of the door opening consists of a hinged or pivotally mounted fire stop carried by said lintel; and

Figure 2 is a bottom plan view of the parts shown in Figure 1.

Referring to the drawings, which illustrate the preferred form of my invention. A designates the top section of a counter-

balanced fire door and B designates the lintel of the opening which said door closes, the top section A of the door being spaced away from the lintel B, so as to provide a space for receiving the bottom section of the vertically-aligned door located at the floor above when said bottom section is moved downwardly into its open position. In order to prevent fire from escaping through the space between the top section A of the door and the lintel B a fire stop C is provided for normally closing said space, said fire stop being mounted on the lintel B in such a manner that it will open automatically or move into an inoperative position when the bottom section of the door above is moved downwardly through the space between the lintel B and the top section A of the door shown in Figure 1. The fire stop C can be mounted in various ways without departing from the spirit of my invention, but when the lintel of the door opening is formed by angles or metal plates, it is preferable to pivotally mount the fire stop C on the lintel and provide said fire stop with one or more counter weights D that normally hold said fire stop in a horizontal position, as shown in full lines in Figure 1, so as to effectively close the space between the lintel and the top section of the door. One convenient way of mounting the fire stop C is to provide it with hinge members 1 that are pivotally connected by pivots 2 to hinge members 3 carried by the lintel B, said fire stop consisting of a metal plate provided with angularly-disposed arms 4 on which weights D are adjustably mounted. When the door is of the type that comprises a binder or other suitable device at the upper end of the door opening for preventing the top section of the door from pulling away or springing away from the lintel, as described in my prior U. S. Patent No. 1,034,848, dated August 6, 1912, I prefer to provide the top section of the door with a depending pin or other device 5 arranged at the upper edge of same, as shown in Figure 1, and provide the fire stop C with an extension 6 having an opening 7 in same for receiving the binding device 5 when the top section of the door is in its closed position, said extension 6 projecting into a substantially channel-shaped, vertical housing 8 on the top section A of the door, as shown in Figure 2.

In an elevator fire door structure of the

character above described there is no liability of fire escaping from the elevator shaft into the room or from the room into the elevator shaft over the upper edge of the top section of the door when the door is closed, due to the fact that the space between the top section of the door and the lintel B of the door opening is closed by the fire stop C. While said fire stop effectively closes the space between the top section of the door and the lintel of the door opening, it does not interfere with the upward movement of the top section of the door or the downward movement of the bottom section of the vertically-aligned door located at the floor above, owing to the fact that said stop is mounted in such a way that it will swing downwardly into an inoperative position, as shown in broken lines in Figure 1, when it is engaged by the bottom section of the door above during the operation of opening the latter. As soon as the door above is closed, the fire stop C will return automatically to its normal closed position, and as it is provided with a means that co-operates with a part on the top section of the door to prevent the intermediate portion of said top section from springing away from the fire stop when said top section is subjected to excessive heat from a fire, said fire stop serves not only as a closure for the space between the top section of the door and the lintel of the door opening, but also as a means for securely holding the top section of the door in position and preventing it from bulging or buckling into such a shape that fire can pass over the upper edge of the door either into the elevator shaft or from the shaft into the room.

Having thus described my invention, what I claim as new and desire to secure by Letters Patent is:

1. An elevator fire door structure, comprising a top door section spaced away from the lintel of the door opening so as to form a passageway for vertically aligned door located at a higher level, and an oscillating fire stop carried by the lintel that normally acts as a closure for the space between said door section and lintel when said top door section and the door above are in their closed position.

2. An elevator fire door structure, comprising a top door section spaced away from the lintel of the door opening so as to form a passageway for the bottom section of a vertically-aligned door located at the floor above, and a pivotally mounted fire stop that normally acts as a closure for the space between said door section and lintel when said top door section and the door above are in their closed position, said fire stop being carried by a part that is stationary with respect to said bottom section and adapted to be moved into an inoperative position by said bottom section when it is depressed, and means for restoring said fire stop to its normal operative position when said bottom door section is thereafter raised.

3. In an elevator fire door structure of the type in which the door comprises a vertically-movable top section that is spaced away from the lintel of the door opening, for the purpose described a fire stop pivotally mounted on said lintel for normally closing the space between said lintel and said top door section.

4. In an elevator fire door structure of the type in which the door comprises a vertically-movable top section that is spaced away from the lintel of the door opening, for the purpose described a fire stop pivotally mounted on said lintel for normally closing the space between said lintel and said top door section, and a counter weight combined with said fire stop for normally maintaining it in its closed position.

5. In an elevator fire door structure of the type in which the door comprises a vertically-movable top section that is spaced away from the lintel of the door opening for the purpose described, a fire stop pivotally mounted on said lintel for normally closing the space between said lintel and said top door section, counterweights combined with said fire stop for normally maintaining it in its closed position, and means on said fire stop that co-operates with the top section of the door to prevent the intermediate portion of said top section from springing away from the fire stop when said top section is subjected to excessive heat from a fire.

HERMAN C. WALDMAN.
